UNITED STATES PATENT OFFICE.

JOHN S. VRAHORITIS, OF DETROIT, MICHIGAN, ASSIGNOR OF ONE-HALF TO STANLEY J. ABRONAITIS, OF DETROIT, MICHIGAN.

ELEVATOR-STOP MECHANISM.

Application filed July 11, 1927. Serial No. 204,743.

This invention relates to elevator stop mechanisms and the object of the invention is to provide a means for stopping an elevator automatically upon breakage of the elevator cable.

Another object of the invention is to provide a stop mechanism normally maintained in inoperative relation by the elevator cable and adapted to be automatically actuated upon breakage of the elevator cable.

Another object of the invention is to provide an elevator stop mechanism consisting of levers pivotally secured to the top and bottom of the elevator and actuated simultaneously upon breakage of the elevator cable to engage in toothed racks provided therefor in the elevator shaft.

These objects and the several novel features of the invention are hereinafter more fully described and claimed and the preferred form of construction by which these objects are attained is shown in the accompanying drawings in which—

Fig. 1 is a side elevation of an elevator equipped with my improved stop mechanism.

Fig. 2 is a plan view thereof.

Fig. 3 is a section taken on line 3—3 of Fig. 2.

As will be understood from Figs. 1 and 2 the elevator 1 is slidable in the ways 2. A series of four brackets 3 are secured to the top of the elevator, each having a pin 4 extending through a slot 5 in the respective lever 6. These pins 4 provide pivots for the levers 6

and the levers 6 are connected together in pairs by the hinges 7 shown in Figs. 1 and 2. Each lever is enlarged adjacent the hinge 7 to provide abutting ends 8 above the hinge 7 and abutting ends 9 below the hinge 7. These abutting ends 8 and 9 limit turning movement of the levers 6 on the pivot 7. The levers on opposite sides of the hinges 7 are connected together by the bars 10 as shown more particularly in Fig. 2. A hinge 11 is provided over the center of the elevator and is connected to two members 12 which, as shown in Fig. 2, are connected to the cross bars 10. The hinge 11 is mounted so that its axis is in alignment with the axes of the hinges 7 and the members 12 are provided with apertures 13 through which the elevator cables 14 extend. These elevator cables 14 are secured in a mounting 15 secured to the top of

the elevator cage and a collar 16 is secured to each cable 14 and engages beneath the members 12 as shown in Fig. 3 which holds the members 12 and pivot 11 in the raised position with the levers 6 out of engagement with the racks 17 provided therefor in the elevator shaft. This position of the hinged pivot 11 is communicated through the members 12 and cross bars 10 to hold the pivots 7 in alignment with the pivot point 11 and with the abutting faces 9 of the levers in engagement beneath the hinges 7. Brackets 18 are secured to the top of the elevator and springs 19 are connected to these brackets and to the pins 20 extending from the levers 6. When the parts are in the inoperative position shown in full lines in Fig. 1 the springs 19 are extended as shown. As shown in Figs. 1 and 2 an arm 21 is pivotally connected to each lever 6 and extends downwardly below the bottom of the elevator and is pivotally connected to a companion lever 6^a which is an exact duplicate of the lever 6. Brackets 3^a are provided on the bottom of the elevator which are similar to the brackets 3 and provide pivots for the levers 6^a. By providing the arms 21 the levers 6^a are operated in conjunction with the levers 6 so that the stop mechanism engages in the racks at both the top and bottom of the elevator cage. A stop 22 is provided on the bottom of the elevator for each lever 6^a and against which the levers 6^a are adapted to engage when in the locked position as shown in dotted lines in Fig. 1.

In operation the elevator travels up and down in the elevator shaft with the parts in the position shown in full lines in Fig. 1. Should the cables 14 break the collars 16 are unsupported and the springs 19 draw the inner ends of the levers 6 and the hinges 7 downwardly until the end faces 8 of the levers engage thus moving the levers 6 outwardly on the pivots 4 into engagement in the toothed racks 17. This movement of the levers 6 is communicated by means of the pivoted arms 21 to the levers 6^a which are also moved into engagement with the racks 17 and the levers 6^a also engage against the stops 22 which rigidly supports the elevator and the arms 21 take the direct strain of supporting the ends of the upper levers 6 in the racks. To release the locking arrangement it is only necessary to repair the break in the cables and again

lift the elevator by the cable hoisting mechanism at which time the stop mechanism will automatically disengage from the racks and is ready for subsequent action upon breaking 5 of the cable.

From the foregoing description it becomes evident that the device is very simple and efficient in operation, provides a safety device for the elevator at all times which is automatically operated by breakage of the cable and provides a device which accomplishes the objects described.

Having thus fully described my invention, its utility and mode of operation, what I 15 claim and desire to secure by Letters Patent of the United States is—

1. In an elevator stop mechanism, an elevator cage, a series of hoisting cables attached thereto, a pair of levers at each side of the 20 cage hingedly connected together at the abutting ends, each lever being provided with a slot intermediate its ends, a bracket for each lever secured to the top of the elevator cage, a pin secured in each bracket and extending 25 through the slot in the respective lever, a series of racks in the elevator shaft adapted to be engaged by the ends of the levers, means supported on the cables normally holding the levers out of engagement with the racks, a 30 series of springs adapted to throw the levers into engagement with the racks upon breakage of the elevator cables, a series of levers on the bottom of the elevator cage adapted to be actuated in conjunction with the levers 35 on the top of the elevator cage and a series of stops on the bottom of the elevator cage limiting upward movement of the lower levers when in engagement with the racks.

2. In an elevator stop mechanism, an elevator cage, a series of hoisting cables attached thereto, a pair of levers at each side of the 40 cage each pivotally mounted intermediate its ends on the top of the cage, each pair of levers

being hingedly connected together at the abutting ends, a series of racks in the elevator 45 shaft adapted to be engaged by the ends of the levers, means supported on the cables normally holding the levers out of engagement with the racks, a series of springs tending to throw the levers into engagement with the 50 racks upon breakage of the elevator cables, a series of levers pivotally mounted on the bottom of the cage corresponding in position to the levers on the top of the cage, and an arm connecting each lever on the top of the cage 55 with the respective lever on the bottom of the cage for simultaneously actuating the lower lever with the respective upper lever.

3. In an elevator stop mechanism, an elevator cage, a series of hoisting cables attached thereto, a pair of levers at each side of the cage each pivotally mounted intermediate its ends on the top of the cage, each pair of levers being hingedly connected together 60 at the abutting ends, a series of racks in the elevator shaft adapted to be engaged by the 65 ends of the levers, means supported on the cables normally holding the levers out of engagement with the racks, a series of springs tending to throw the levers into engagement 70 with the racks upon breakage of the elevator cables, a series of levers pivotally mounted on the bottom of the cage corresponding in position to the levers on the top of the cage, an arm pivotally connecting each lever on 75 the top of the cage with the respective lever on the bottom of the cage for simultaneously actuating the lower lever with the respective upper lever, each pair of levers being provided with faces at the abutting ends arranged to come into contact as the ends of the 80 levers are moved into the racks to limit turning movement of the levers on their pivots.

In testimony whereof I sign this specification.

JOHN S. VRAHORITIS.
